UNITED STATES PATENT OFFICE.

JOSEPH SINCLAIR FAIRFAX, OF LONDON, ENGLAND.

VARIABLE-SPEED GEAR.

SPECIFICATION forming part of Letters Patent No. 740,545, dated October 6, 1903.

Application filed July 14, 1902. Serial No. 115,457. (No model.)

To all whom it may concern:

Be it known that I, JOSEPH SINCLAIR FAIRFAX, a subject of the King of the British Dominions, whose post-office address is 37 and 39 Essex street, Strand, London, England, have invented certain new and useful Improvements in Variable-Speed Gear, (for which I applied for British Letters Patent May 31, 1902, No. 12,321,) of which the following is a specification.

My invention relates to improvements in variable-speed gear by which when worked in one direction the revolutions per minute of the motor or driving shaft are reduced in number at the driven part and adapted to give a plurality of reduced speeds. With these may be combined means for obtaining other speeds, thus giving a choice of two or more speeds. When worked in the opposite direction to that indicated above, the speed of the aforesaid shaft is increased proportionately, which reversible character being a well-known property of many forms of variable-speed gear will not be claimed by itself apart from the means of producing it; but to prevent confusion my invention will be described as if it were always driven by a central shaft, which is caused to operate certain wheels or pulleys the periphery of which will be considered as the driven part, and the points of novelty relied on will be set out in the claims.

The invention is applicable to the main shaft of quick-running motors, oil, gas, or other engines, but may be combined with a counter-shaft. It is adapted for driving velocipedes, motor-car or similar road or rail vehicles, machine-tools, or for other useful purposes either by belting or by toothed gearing.

In the further description of this invention reference is made to the accompanying drawings, in which—

Figure 1 is a longitudinal vertical section through a four-speed gear. Fig. 2 is an end elevation of the same, and Fig. 3 is a transverse section through Fig. 1. Fig. 4 is a longitudinal vertical section through a two-speed gear, which is virtually one-half of the four-speed gear shown in Fig. 1, but with slight changes in the details of construction due to its smaller dimensions. Fig. 5 is an end elevation of Fig. 4 on the frame or support side. Fig. 6 is also an end elevation of Fig. 4 on

the opposite side to Fig. 5, but showing a cross-head and slide movement, explained hereinafter with reference to Fig. 7, which is a similar section to Fig. 4, but with one set of the pinion-teeth removed. Fig. 8 is a longitudinal view of a four-speed gear, (a modification of Fig. 1,) the upper half being in section and the lower half in elevation.

In all of the drawings pulleys adapted for belt-driving are shown of equal diameter, so that a flat belt may be readily shifted from one pulley to the adjoining one in each two or four speed arrangement; but it will be readily understood that the wide flanges may be dispensed with and spur gear-wheels used instead, as shown in Fig. 8 and indicated by dotted lines in Fig. 1, and that references to pulleys equally apply to spur gear-wheels.

In the drawings, *a* denotes any suitable form of frame or support to a compound bearing *b*, which may either be cast integral with the frame *a*, as shown on the right-hand side of Fig. 1, or formed separately and fitted therein, as indicated on the left-hand side of the same figure. This compound bearing *b* is an important part of my invention, and it is bored to receive a central driving-shaft *c*, which is journaled and rotatable therein. The shaft *c* may form the main shaft of an engine or motor or a counter-shaft driven by any other means. The shaft *c* carries a compound pinion *d*, secured thereto in Fig. 1, having four sets of teeth *d'*, *d''*, *d'''*, and *d''''*, varying in diameter and engaging with the internal teeth of a series of wheels *e*, *f*, *g*, and *h* of corresponding internal diameters, each of which forms a part of or is secured to a separate pulley, (indicated by the same reference-letter, as *e*, *f*, *g*, and *h*.) These pulleys are all of the same external diameter and, as shown, are adapted for belt-driving, the belt being moved by well-known means from the slowest-moving pulley *e*, for example, to *f*, the next fastest, and so on to *g* and *h*, the quickest, or back again, as required.

It will be readily understood that the wide flanges of the pulleys may be dispensed with and gear-teeth formed on the periphery instead, as indicated by Fig. 8, if it is desired to drive by toothed gearing, in which case a sliding spur-wheel (not shown) on a shaft arranged parallel with *c* may be brought in successive

contact with the teeth on e , f , g , and h to be driven at various rates of speed or thrown out of gear by placing it in the wide spaces between the teeth.

- 5 To allow the several sets of pinion-teeth to engage with and clear themselves of the internal teeth surrounding them, the wheels e' and f' (engaging with d' and d^2 , respectively) are mounted upon and revolve on an axial line 10 eccentric to but parallel with the axial line on which the pinion-teeth d' and d^2 revolve. This is done by forming the outside of the compound bearing b eccentric to the interior bore for the shaft c and fitting the hub of the 15 internal toothed wheel e' directly on the outside of the bearing b , so as to turn freely thereon, and similarly fitting the enlarged hub of the internal toothed wheel f' on the hub of e' , as shown in Fig. 1.
- 20 To allow the parts to be fitted together, the hub of e' is prolonged as a sleeve the full length of the bearing b and the external portion of the pulley e is secured to the sleeve e' by a set-screw j or other suitable means after 25 the portion f of the adjoining pulley has been placed on the sleeve e' . The overhanging portion f' , which carries the internal teeth meshing with d^2 , is screwed to and completes the pulley f , and thus the latter has an independent motion and speed from the pulley e , 30 driven by d' , due to the ratio between the numbers of their teeth.

The internal toothed wheel g' (being the overhanging portion of the pulley g) meshes 35 with the set of pinion-teeth d^3 , and the internal toothed wheel h' meshes with the set of pinion-teeth d^4 in a similar manner to e' with d' and f' with d^2 . The pulleys g and h are also similarly connected to their respective 40 internal toothed portions g' and h' , as before described. Likewise h' has a prolonged sleeve fitted to revolve freely upon the eccentric compound bearing b , which is also bored for the prolonged shaft c and supported by the 45 frame a . It will be seen, therefore, that the essential elements of my invention consist of a frame or support carrying a compound bearing, in which is a rotatable shaft adapted by its rotation to drive a pinion, which meshes 50 with an internal toothed wheel rotatable on the outside of the compound bearing, the revolution of the pinion being upon an axis eccentric to the axis on which the wheel is rotatable. By combining two such wheels so 55 as to rotate upon the same axis and driving them by two sets of pinion-teeth having diverse diameters and revolving in eccentric relation to the axis of the wheels two speeds are obtainable, both working in the same direction. An example is given in Fig. 4 which 60 is adapted to drive a motor-bicycle. By extending the shaft c and duplicating the other parts (with slight modifications in form and dimensions) the four-speed gear already described with reference to Fig. 1 is produced.

The frame or supports a for a four-speed gear may be made in two distinct halves and

bolted together by bolts and nuts a^1 and a^2 , as shown in Figs. 1, 2, and 3, or formed integral as a base, with the compound bearings 70 b bolted on through lugs. Two single bases a , of the type shown in Figs. 4, 5, 6, and 7, may be combined and screwed to a base with an extended shaft c through both compound bearings b to form a four-speed gear, or when 75 used singly the support a may form a part of the crank case or frame of the engine-motor.

In the two-speed gear shown in Fig. 4 the overhung portion e' of the pulley e , which is formed with internal teeth, is made integral 80 with the pulley instead of being in two portions, as in Figs. 1 and 8. The pulley f and internal toothed portion f' are similarly formed integral, an extended flange from f being fitted to rotate upon the outer surface 85 of the part e' . In this example it is preferred to make the pinion d in two distinct pieces d' and d^2 , which, as shown in Fig. 4, would drive the two pulleys e and f at two different speeds, both reduced from that of the driving-shaft 90 c ; but by removing d^2 , as shown in Fig. 7, and fitting the cross-head c^3 to slide upon the flattened sides of the shaft c and movable at right angles in the lugs f^2 , formed on the face of the pulley f , Fig. 6, a speed equivalent to that 95 of the shaft c is imparted to the pulley f , and a washer c^2 is adapted to keep the parts in place or is formed as c^2 in Fig. 4 for the same purpose.

What I claim, and desire to secure by Letters Patent of the United States, is—

1. A variable-speed gear having in combination a stationary tubular bearing, revoluble wheels mounted on the exterior thereof, a revoluble shaft journaled in said bearing, and intervening rotatable means engaging with said shaft and said wheels, substantially as set forth.

2. A variable-speed gear having in combination a stationary bearing, revoluble wheels 110 mounted thereon having the same external diameter, a revoluble shaft journaled in said bearing and having means to actuate said wheels at diverse speeds, substantially as set forth.

3. A variable-speed gear having in combination a stationary bearing, revoluble wheels mounted on said bearing, a revoluble shaft journaled in said bearing, and between said wheels and said shaft intervening rotatable 120 means having an axis of rotation eccentric to the axis of said wheels to operate them at diverse speeds, substantially as set forth.

4. A variable-speed gear having in combination a stationary bearing, a revoluble shaft 125 journaled in said bearing, a revoluble wheel mounted on said bearing, a second wheel mounted to rotate concentrically with the first, and intervening means rotatable on an eccentric axis engaging with said wheels and said shaft, substantially as set forth.

5. A variable-speed gear having in combination a compound bearing, a revoluble shaft journaled therein, a plurality of wheels hav-

- ing internal teeth mounted and revoluble on said compound bearing, and a compound pinion mounted on said shaft meshing with said internal teeth, substantially as set forth.
- 5 6. A variable-speed gear having in combination a compound stationary bearing, a revoluble shaft journaled therein, a plurality of wheels of the same exterior diameter but each having internal teeth of diverse diameter mounted on said bearing, a pinion secured to said shaft having teeth engaging with said internal teeth, and means to rotate said pinion on an axis eccentric to the axis of rotation of said wheels, substantially as set forth.
- 15 7. A variable-speed gear having in combination a compound bearing, means to support the same, revoluble wheels mounted thereon, a revoluble shaft journaled therein, and a pinion adapted to operate said wheels by said shaft in eccentric relation to their axis at diverse speeds, substantially as set forth.
8. In a variable-speed gear, the combination of a tubular bearing, a revoluble member on the outside of said bearing, a revoluble member inside said bearing having an axis of rotation eccentric to that of said outside member, and a frame supporting said bearing in stationary relation to said revoluble members, substantially as set forth.
- 25 9. In a variable-speed gear, a compound bearing, a rotatable shaft journaled therein adapted to operate a driving member rotatable on an axis eccentric to the axis of the exterior of the said bearing, substantially as set forth.
- 30 10. In a variable-speed gear, the combination of a driving member, and a driven member, with a compound bearing adapted to keep them in rotatable eccentric relation substantially as set forth.
- 35 11. In a variable-speed gear, the combination of a driving member, a driven member, a stationary bearing, and means to keep said driving and driven members in rotatable and eccentric relation to each other, substantially as set forth.
- 45 12. In a variable-speed gear, the combination of a stationary tubular bearing, revoluble wheels mounted on the exterior of said bearing, and means for actuating said wheels at diverse speeds, substantially as set forth.
- 50 13. In a variable-speed gear, the combination of a stationary bearing, revoluble members mounted thereon, a rotatable shaft journaled therein, and means for communicating rotary motion from said shaft to said members or reversely, substantially as set forth.
- 55 14. In a variable-speed gear, the combination of a stationary bearing, revoluble members mounted thereon, a shaft journaled therein, and a pinion adapted to communicate rotary motion between said shaft and said members, substantially as set forth.
- 60 15. In a variable-speed gear, the combination of a stationary bearing, revoluble members mounted thereon, a shaft journaled therein, and a compound pinion, adapted to communicate rotary motion between said shaft and said members, having its axis of rotation eccentric to the axis of said members, substantially as set forth.
- 65 16. In a variable-speed gear the combination of two compound bearings in line, one or more revoluble members mounted on each bearing, and a revoluble member journaled in said bearings, substantially as set forth.
- 70 75 In testimony whereof I have signed this specification in the presence of two subscribing witnesses.
